ADJUSTABLE STAND FOR ROTATABLE BALANCES

Filed Jan. 16, 1929

UNITED STATES PATENT OFFICE

WILLY PAUL JENNY, OF STRASBURG, OHIO, ASSIGNOR TO THE FIRM EXPLORATION
G. M. B. H., OF HANOVER, GERMANY

ADJUSTABLE STAND FOR ROTATABLE BALANCES

Application filed January 16, 1929, Serial No. 332,899, and in Germany January 9, 1928.

The present invention relates to an adjustable stand for a rotatable balance for executing geophysical measurements that is such measurements which try to establish the nature of the ground in regard to its homogeneity by determining the local attraction of masses by means of two exactly equal weights suspended at different heights on both ends of a balance beam according to the Eotvos principle.

The annexed drawing represents a sectional elevation of the adjustable stand for the rotatable balance. According to the drawing there is a circular base plate 1 fixed to the end of a cylindrical hollow column 2 on the outside of which a fourfold thread 3 is cut. This screw thread fits exactly a corresponding female thread of a tube 4 which is revolvably held within a vertical stand 5 bolted to a pedestal 6 by means of the bolts 13. The tube 4 rests with an annular member secured to its top end on a ball bearing 7 carried by the top of the stand 5 and rests with its bottom on a second ball bearing 8 carried by a bottom plate 9 closing the underside of the pedestal 6. The tube 4 can be rotated by means of a conical gear wheel 10 which is engaged by a pinion 11 keyed to an axis 12 provided with a socket for a socket-wrench. The revolving of said tube is prevented in one direction by a spring operated pawl 14 engaged into the ratchet 15 provided on the top side of gear wheel 10.

In order to retain the column 2 from rotation while tube 4 is revolved and in order to produce by this rotation the raising of column 2 and of the base plate 1 a vertical shaft 16 is arranged concentrically to the tube 4 and revolvably within the hub of gear wheel 10. This shaft 16 is provided with a longitudinal groove 17 and engages thereby a cog projecting from a collar 18 fixed to the inside of the column 2.

The shaft 16 is supported by a step bearing 19 and is driven by means of a bevel wheel 20

meshing with a pinion 21 on an axis 22. This axis journalled in a bottom plate 9 receives its revolving movement by means of the conical gears 23, 24 from a vertical shaft 25, which is connected by means of two other pinions 26 and 27 with a gearing 28 and 29. This gearing is represented only in part. It controls a regulating device the power of said device being employed to keep up the oscillations of a pendulum 31. The length of this pendulum may be increased or diminished in order to adjust the rate of descent of the column with the base plate 1.

The represented arrangement is operated as follows: When the measuring device is mounted the wrench fitting the square of the axis 12 is put in and turns the tube 4 in the direction allowed by the pawl 14. The column 2 cannot turn because it is prevented therefrom by the cog of the collar 18 engaged in the groove of shaft 16. The shaft 16 itself is blocked by means of the gearing described here above and by means of the regulating device, the pendulum of which is blocked at this moment.

The turning of the tube 4 will cause a rising movement of column 2, of base plate 1 and of the balance mounted thereon. The rising movement will be stopped when the cog of the collar 18 strikes against the end of the groove 17. Now the pendulum is released and started by a touch and the whole mechanism begins running. Under the effect of its weight increased by that of the balance the column 2 begins to sink with a speed which is a function of the length of the pendulum 31. At the same time the column will turn at a speed which is determined by the pitch of the thread 3. The tube 4 however is blocked by the pawl 14.

The movement continues until the tube is at the end of its path. In this moment the sinking as well as the rotating movement of the base plate will be stopped.

What I claim is:

1. In an adjustable stand for a rotatable balance for executing geophysical measurement, a support of the measuring device, means for simultaneously turning and sinking said support and means for regulating such turning and sinking movements.
2. In an adjustable stand for a rotatable balance for executing geophysical measurements, a support of the measuring device comprising a tubular vertical stand, two concentrically arranged tubes held rotatably within said stand, the inner tube constituting the carrier of the measuring device, steep pitched screw threads as interlocking means between said inner and outer tube so as to adapt said inner tube to turn and sink simultaneously inside of the outer tube under the effect of its dead weight and means for regulating such turning and sinking of the inner tube.
3. In an adjustable stand for a rotatable balance for executing geophysical measurements, a support of the measuring device comprising a tubular vertical stand, two concentrically arranged tubes held rotatably within said stand, the inner tube constituting the carrier of the measuring device steep-pitched screw threads as interlocking means between said inner and outer tube so as to adapt said inner tube to turn and sink simultaneously inside of the outer tube under the effect of its dead weight, a pedestal constituting the base of said stand, a grooved shaft standing in a step bearing of said pedestal and held slidably but not rotatably within said inner tube, a pendulum regulator attached to said pedestal and capable of controlling the amount of the two movements of said inner tube and an intermediate transmission gear between grooved shaft and regulator.
4. In an adjustable stand for a rotatable balance for executing geophysical measurements, a support of the measuring device comprising a tubular vertical stand, two concentrically arranged tubes held rotatably within said stand, the inner tube constituting the carrier of the measuring device, steep pitched screw threads and interlocking means between said inner and outer tube so as to adapt said inner tube to turn and sink simultaneously inside of the outer tube under the effect of its dead weight, a pedestal constituting the base of said stand, a grooved shaft standing in a step bearing of said pedestal and held slidably but not rotatably within said inner tube, a pendulum regulator attached to said pedestal and capable of controlling the amount of the two movements of said inner tube, hand controlled means located in the pedestal and adapted to turn the outer of said tubes, and a ratchet-device securing the turning of said tube in one direction only.
5. In an adjustable stand for a rotatable

balance for executing geophysical measurements, a support of the measuring device comprising a tubular vertical stand, two concentrically arranged tubes held rotatably within said stand, the inner tube constituting the carrier of the measuring device, steep pitched screw threads as interlocking means between said inner and outer tube so as to adapt said inner tube to turn inside of the outer tube under the effect of its dead weight.

In testimony whereof I affix my signature.
